UNITED STATES PATENT OFFICE.

LLOYD A. DOLTON, OF CHICAGO, ILLINOIS, ASSIGNOR TO WELLER MANUFACTURING COMPANY, OF CHICAGO, ILLINOIS, A CORPORATION OF ILLINOIS.

METHOD OF AND APPARATUS FOR BACK-FILLING.

1,359,582.

Specification of Letters Patent. Patented Nov. 23, 1920.

Application filed April 18, 1918. Serial No. 229,249.

To all whom it may concern:

Be it known that I, LLOYD A. DOLTON, a citizen of the United States, and a resident of Chicago, in the county of Cook and State 5 of Illinois, have invented certain new and useful Improvements in Methods of and Apparatus for Back-Filling, of which the following is a full, clear, and exact description.

10 The invention relates to apparatus and a method for use in connection with laying or building sewers. Heretofore, it has been the common practice to excavate a trench and deposit the soil at one side of the cut 15 or trench, and leave it there until the sewer has been laid or built. Then it is shoveled back into the trench.

The present invention is designed to avoid the necessity of depositing the excavated 20 material alongside of the trench and to back-fill the trench with material removed therefrom without depositing the soil.

This object is attained by providing an apparatus which is adapted to convey and 25 take care of the excavated material from the time that it is removed from the cut until after the sewer has been laid or built and then back-fill it.

In providing apparatus to attain this result, the necessity of depositing the excavated material on the road or ground at the side of the cut is avoided and back-filling is greatly expedited.

The invention consists in the several novel 35 features hereinafter set forth and more particularly defined by claims at the conclusion hereof.

In the drawings: Figure 1 is a side elevation of an apparatus embodying the invention. Fig. 2 is a vertical transverse section taken on line 2—2 of Fig. 1. Fig. 3 is a plan of that portion of the apparatus which receives dirt from the cut. Fig. 4 is a side elevation of the same. Fig. 5 is a section 45 taken on line 5—5 of Fig. 7. Fig. 6 is an end elevation of the receiving apparatus. Fig. 7 is a vertical longitudinal section of the receiving apparatus. Fig. 8 is an end elevation, and Fig. 9 is a plan of the apparatus for delivering dirt back into the cut.

The apparatus comprises essentially a receiving apparatus A into which the dirt is deposited, usually by a steam shovel, a dirt carrier B supported upon a series of trucks 55 C, and a delivery apparatus D, the conveyer

being of sufficient length to retain and handle the material from the point where it is excavated to the point where the cut is to be closed or where back-filling is to occur after the sewer has been laid or built. The 60 receiving apparatus A is sustained by a wheeled truck a and the delivery apparatus is suitably sustained by a wheeled truck d, so that the entire apparatus can be advanced on rails 10 to keep apace with the digging 65 and back-filling of the cut.

The receiving apparatus comprises a hopper 11 having inclined sides 11^a and vertical ends 11^b, supported by a framework 12 which is built upon the truck a. The hopper 11 is open at the bottom so that the material in the hopper will fall therethrough onto an endless pan conveyer 13 which travels around sprockets 14 on a shaft 15 and sprockets 16 on a shaft 17, which are mounted on the frame-work 12. The upper reach 70 of this pan conveyer is suitably guided between said shafts on tracks 18 which are supported by cross-beams 19. The lower reach of said conveyer is supported on 75 tracks 20. This conveyer is adapted to gradually convey the material deposited in the hopper 11 to an endless conveyer belt 21 which is of sufficient length and capacity to support the material to the point where back-filling is to be done. The pans or buckets 80 of conveyer 13 serve to regularly feed the dirt away from the hopper, the end 11^b being extended to prevent excessive loading. Cutter blades 22 on a shaft 23 are operated 85 to break up the material as it falls from the pan conveyer 13 onto the belt 21 of carrier B.

The receiving end of the endless belt 21 passes around a pulley 24 on a shaft 25 95 which is sustained by the framework 12 on and below the pan conveyer. The cutter shaft 23 is mounted on frame-work 12. A guide pulley 26 is mounted at the rear end of the frame-work 12 and similar pulleys 100 are mounted on trucks C, to support the lower lap of the endless conveyer 21. Belt 21 is driven by power at the delivery apparatus and shaft 25 is driven by said belt. A sprocket wheel 27 on shaft 25 drives a 105 chain 28 which drives a sprocket wheel 29 on shaft 17 to drive the pan-conveyer 13. A gear 30 on shaft 25 meshes with a gear 31 on a shaft 32 which is supported by the frame-work 12, and a sprocket wheel 33 on 110

shaft 32, chain 34, and sprocket wheel 35 on shaft 23 drive the cutters 22.

Between the receiving and delivery apparatus, the upper reach of the conveyer-belt 21 is supported on pulleys 36 and troughing rollers 37 which raise the margins of the belt to retain the dirt. The shafts of these pulleys and rollers are mounted in bearings fixed to the sills 38 which are 10 adapted to rest on the wheeled trucks C. These sills are not fixed to the trucks to permit some flexibility when the apparatus is being moved around a curve. A sufficient number of these trucks are provided to support the conveyer belt B between the receiving apparatus and the delivery apparatus, which are spaced apart a sufficient distance to retain the material from the point where it is received from the cut to the point where 20 the sewer has been laid or built and the trench is to be filled.

At the delivery end of the apparatus, the conveyer belt 21 is elevated and passes around a pulley 40 on a shaft 41 which is 25 supported by suitable frame-work 42 which is carried by the trucks adjacent the delivery end and is secured to sills 38'. A motor 43 is suitably mounted on these sills. A belt 44, driven by the motor, drives a pulley 45 30 on a countershaft 46 which has a pinion 47 which drives a gear 48 on the shaft 41. This motor and gearing drive the conveyer belt 21. The latter, besides conducting the material from the receiving apparatus to 35 the delivery apparatus, drives the shaft 25, from which power is communicated to the pan conveyer 13 and cutters 22, as herein-before described.

The delivery apparatus comprises an endless cross-conveyer 50 which passes around a pulley 51 supported by the frame-work 52 on the truck d of the receiving apparatus, and a pulley 53 mounted adjacent the outer end of a conveyer-frame 54 which is pivotally connected to the frame 52 so it can be swung vertically to vary the point at which the material will be discharged from the belt 50. A suitable hoist 55 is mounted on the frame-work 52 to adjust the cable 56 45 which supports the conveyer frame 54. The longitudinal conveyer belt 21 discharges material into a chute 57 which delivers it into the end of the cross-conveyer 50. A chain 60 is driven by a sprocket wheel 61 on shaft 59 56 to drive a sprocket 62 on a shaft 63. A beveled pinion 64 on shaft 63 drives a gear 65 on shaft 66 of the pulley 51 at the inner end of the cross-conveyer. An inclined apron 70 is adjustably supported so it can 60 deflect the material discharged from the cross-conveyer to the desired point in the trench.

In operation, the material excavated from the cut or trench is deposited into the hopper 65 11 at the receiving end of the back-filling

apparatus. The pan conveyer 13 conducts the material in regulated quantity from the hopper and deposits it on the endless trough-conveyer 21, the cutter 22 serving to disintegrate and break up the material so that it 70 will be in condition to be used for back-filling. The conveyer 21 retains and conducts the material and ultimately discharges it into the hopper 57 which deposits the material into the cross conveyer 50 which conducts it sidewise to a point where it will back-fill the trench after the sewer has been laid. All of the apparatus is driven in synchronism so that it will operate to dispose of the material in regulated quantities and as the excavation and filling occur, the entire apparatus will be moved forwardly on the track, to constantly maintain the receiving apparatus, in position to receive the filling and to advance the delivery apparatus as the trench is filled. The entire apparatus may be continuously driven.

The invention thus exemplifies apparatus which is adapted to receive the excavated material as the trench is formed and to retain it and convey it continuously to the point where the trench is to be filled after the sewer has been laid or built. The apparatus avoids depositing the material onto the roadway and the necessity of picking it 90 up to subsequently fill the trench, and also exemplifies a method for back-filling which avoids depositing the soil onto the roadway or at the side of the cut.

The invention is not to be understood as 100 restricted to the details set forth, since these may be modified within the scope of the appended claims, without departing from the spirit and scope of the invention.

Having thus described the invention, what 105 I claim as new and desire to secure by Letters Patent, is:

1. In apparatus of the character described, the combination of apparatus for receiving material excavated from a trench, 110 a wheeled support for the receiving apparatus, delivery-apparatus disposed relatively to the receiving apparatus to discharge the material into a previously excavated portion of the same trench, a wheeled support for the delivery-apparatus, a conveyer between the receiving apparatus and the delivery apparatus, and wheeled supports for the conveyer between the receiving apparatus and the delivery apparatus.

2. In apparatus of the character described, the combination of apparatus for receiving material excavated from a trench, 115 a wheeled support for the receiving apparatus, delivery-apparatus disposed relatively to the receiving apparatus to discharge the material into a previously excavated portion of the same trench, a wheeled support for the delivery-apparatus, a cross-conveyer mounted on the support for the 120 125 130

delivery apparatus, a conveyer between the receiving apparatus and the delivery apparatus and wheeled supports for the conveyer between the receiving apparatus and the delivery apparatus.

3. In apparatus of the character described, the combination of apparatus for receiving material excavated from a trench, a wheeled support for the receiving apparatus, disposed relatively to the receiving apparatus to discharge the material into a previously excavated portion of the same trench, a wheeled support for the delivery-apparatus, an endless conveyer between the receiving apparatus and the delivery apparatus, wheeled supports for the conveyer between the receiving apparatus and the delivery apparatus, and a pan-conveyer between the receiving apparatus and the endless conveyer for regularly feeding the material to the endless conveyer.

4. In apparatus of the character described, the combination of apparatus for receiving material excavated from a trench, a wheeled support for the receiving apparatus, delivery-apparatus disposed relatively to the receiving apparatus to discharge the material into a previously excavated portion of the same trench, a wheeled support for the delivery-apparatus, an endless conveyer between the receiving apparatus and the delivery apparatus, wheeled supports for the conveyer between the receiving apparatus and the delivery apparatus, means associated with the delivery apparatus for driving the endless conveyer, a pan conveyer between the receiving apparatus and the endless conveyer, and means for driving the pan-conveyer from the endless conveyer.

5. In apparatus of the character described, the combination of apparatus for receiving material excavated from a trench, a wheeled support for the receiving apparatus, delivery apparatus disposed relatively to the receiving apparatus to discharge the material into a previously excavated portion of the same trench, a wheeled support for the delivery-apparatus, a conveyer between the receiving apparatus and the delivery apparatus, wheeled supports for the conveyer between the receiving apparatus and the delivery apparatus, and means for disintegrating the material delivered to the conveyer.

6. In apparatus of the character described, the combination of apparatus for receiving material excavated from a trench, a wheeled support for the receiving apparatus, delivery-apparatus disposed relatively to the receiving apparatus to discharge the material into a previously excavated por-

tion of the same trench, a wheeled support for the delivery-apparatus, an endless conveyer between the receiving apparatus and the delivery apparatus, wheeled supports 65 for the conveyer between the receiving apparatus and the delivery apparatus, means associated with the delivery apparatus for driving the endless conveyer, means for disintegrating the material delivered to the 70 endless conveyer, and means operated by the conveyer for driving the disintegrating means.

7. In apparatus of the character described, the combination of apparatus for 75 receiving material excavated from a trench, delivery apparatus disposed to discharge the material where the trench is to be filled, a pan-conveyer for removing the material from the hopper in regulated quantities, a 80 conveyer between the pan-conveyer and the delivery apparatus, a motor for driving one conveyer and driving means between the conveyers.

8. In apparatus of the character described, the combination of receiving apparatus comprising a hopper, an endless pan conveyer at the bottom of the hopper, an endless conveyer to receive the material from the pan conveyer, delivery apparatus 90 comprising a cross-conveyer, for receiving the material from the endless conveyer, and wheeled trucks for supporting the receiving apparatus, and all of said conveyers.

9. In apparatus of the character described, the combination of receiving apparatus comprising a hopper, an endless pan conveyer at the bottom of the hopper, an endless conveyer to receive the material from the pan conveyer, delivery apparatus comprising 100 a cross-conveyer for receiving the material from the endless conveyer, wheeled trucks for supporting the receiving apparatus and all of the conveyers, and driving mechanism for all of said conveyers supported by the wheeled trucks.

10. In apparatus of the character described, the combination of receiving apparatus comprising a hopper, an endless pan conveyer at the bottom of the hopper, 110 means associated with the pan conveyer for disintegrating the material, an endless conveyer to receive the material from the pan conveyer, delivery apparatus comprising a cross-conveyer for receiving the material 115 from the endless conveyer, wheeled trucks for supporting the receiving apparatus, the belt conveyer and the cross-conveyer, and means for driving the pan conveyer and the disintegrating means from the belt conveyer.

LLOYD A. DOLTON.
